(57) **CLAIM**

The ornamental design for a footwear outsole, substantially as shown and described.

DESCRIPTION

FIG. 1 is a bottom plan view of a footwear outsole showing my new design;

FIG. 2 is a top plan view thereof;

FIG. 3 is a left side elevational view thereof, the right side elevational view being a mirror image;

FIG. 4 is a front elevational view thereof; and,

FIG. 5 is a rear elevational view thereof.

The broken lines shown in the drawings are for illustrative purposes only and form no part of the claimed design.
